CLAIM

The ornamental design for a surgical tool, as shown and described.

DESCRIPTION

FIG. 1 is an overhead perspective view of a surgical tool. FIG. 2 is an underside perspective view of the surgical tool. FIG. 3 is an underside perspective view of an alternative position of the surgical tool.

FIG. 4 is a top plan view of the surgical tool.

FIG. 5 is a bottom plan view of the surgical tool.

FIG. 6 is a right side elevational view of the surgical tool, the left side elevational view being a mirror image of the right side elevational view.

FIG. 7 is a front elevational view of the surgical tool; and, FIG. 8 is a rear elevational view of the surgical tool.

1 Claim, 7 Drawing Sheets
